UNITED STATES PATENT OFFICE.

ELIZABETH MEARS SMOCK, OF ASHEVILLE, NORTH CAROLINA.

AUTOMOBILE DRIVER'S HEEL PROTECTOR.

Application filed December 22, 1925. Serial No. 77,005.

This invention relates generally to the art of boots, shoes and the like, and has more particular reference to a protector for association with the heel portions of ladies' 5 shoes for use only in the operation of an automobile in order that the heel portions of the shoes will not become marred or dirtied during the operation of a vehicle.

The primary object of the invention is to 10 substantially improve and simplify articles of this type that have been previously patented with which I am generally familiar.

Other objects will become apparent as the 15 nature of the invention is better understood, the same comprising the novel construction hereinafter more fully described and shown in the accompanying drawings and claim.

In the drawing wherein like reference 20 characters indicate corresponding parts throughout both of the views:

Figure 1 is a side elevation of my improved shoe attachment in use, and

Fig. 2 is a detail vertical section thereof.

Now having particular reference to the 25 drawing, my novel shoe attachment includes a strip of flexible material 5 of leather preferably, that is cut and formed as to agree with the contour of the side and rear portions of the heel A of a woman's shoe B 30 as well as the side and rear portions of the upper C at the heel end thereof.

In order that the attachment may be prevented from slipping upwardly from the heel and upper of the shoe, when applied, 35 the same is provided within its lower end with a properly shaped lift of wood or leather 6 to the side and rear edges of which is secured the material forming the attachment through the medium of tacks or 40 the like 7. A strip of leather or other material similar to the material forming the attachment 5 and designated 8 is disposed around the open side of the attachment at its lower end, the same being also secured 45 at its lower edge to the lift 6 as well as to the material forming the attachment pref-

erably by stitching 9, this strip of leather 8 effectively preventing rearward displacement of the attachment with respect to the shoe.

Secured at one end to the inner side of the material forming the attachment is a strap 10 that is adapted to engage over the instep portion of the wearer's foot, and is provided at its opposite end with one or more button 50 holes 11 for receiving a button 12 upon the other side of the material forming the strip in order that the attachment will be positively secured to the shoe of the wearer.

Preferably, the attachment carries a reinforcing strip 13 at its upper rear side for providing an additional protection for the heel portion of the shoe upper C when the foot of the wearer is resting upon the accelerator of the automobile.

It will thus be seen that I have provided a highly novel, simple, and useful attachment for automobile drivers' shoe heels that is a substantial improvement over protectors of a similar nature, and one that will, I 70 believe, meet with ready favor when placed upon the market.

Having thus described my invention, what I claim as new and desire to secure by Letters Patent is:

As a new article of manufacture, a ladies' shoe and heel protector of the class described comprising a pocket constructed of flexible material and shaped to conform to the rear portion of the shoe and rear and side portions of a high heel, a reinforcing patch on the upper part of the pocket and on the rear side thereof, a lift constituting the bottom of the pocket, a strip of flexible material extending across the open side of the bottom 80 of the pocket and serving to confine the heel in said pocket and in engagement with said lift, and a retaining strap for the protector adapted to extend across the instep of the wearer.

In testimony whereof I affix my signature.
ELIZABETH MEARS SMOCK.
